UNITED STATES PATENT OFFICE.

CHARLES F. DEARTH, OF EAST SANGERVILLE, MAINE.

FLOOR-CLAMP.

SPECIFICATION forming part of Letters Patent No. 319,464, dated June 9, 1885.

Application filed March 14, 1885. (No model.)

To all whom it may concern:

Be it known that I, CHARLES F. DEARTH, a citizen of the United States, residing at East Sangerville, in the county of Piscataquis and 5 State of Maine, have invented new and useful Improvements in Floor-Clamps, of which the following is a specification, reference being had to the accompanying drawings.

My invention relates to floor-clamps; and it 10 has for its object to provide a device of this character which shall be simple in its construction, effective in its operation, and one that will be strong and durable.

With these ends in view the invention consists in the combination, with a suitable frame, 15 of a sliding rack-bar, a pivoted jointed arm to engage the teeth of the rack-bar, a lever for operating the pivoted jointed arm, and a pivoted pawl or stop.

20 The invention further consists in the improved construction and combination of parts hereinafter fully described, and pointed out in the claim.

In the drawings, Figure 1 is a perspective 25 view of a floor-clamp embodying my invention. Fig. 2 is a longitudinal vertical section, and Fig. 3 is a transverse vertical section. Fig. 4 is a detail view.

In the accompanying drawings, in which 30 like letters of reference indicate corresponding parts in all the figures, A represents a suitable base-plate, which is preferably cast, said frame being open near its front end and provided with grooves a.

35 B represents a plate having outwardly-extending wings or flanges b, which are adapted to fit the grooves a in the base A. Upon the upper side of the plate B are provided a series of teeth, c.

40 Pivoted to the forward end of the sliding plate B is a bracket, C, having a longitudinal groove or channel, d, on its front edge or face, adapted to receive the tongue of the board being held in position preparatory to permanently securing the same.

45 E represents arms extending upwardly from the sides of the base A, and between said arms, at the lower forward ends thereof, is pivoted a pawl or stop, F, consisting of two short arms, 50 e, connected at their outer ends by a cross-piece, g, which is inclined or set at an angle,

and is adapted to engage the teeth on the sliding rack-plate B and hold it against backward movement.

At the rear end of the base A are provided 55 upwardly-extending ears or lugs h, between which is pivoted a jointed arm, G, the forward end of which is adapted to engage the teeth of the sliding rack-plate B.

I represents a bell-crank lever, which is pivoted between the arms E at the upper ends of the same. The said bell-crank lever is connected with the jointed arm G at the joint of the same by a short arm, J.

The base-plate A is provided on its under 65 side, at the rear end thereof, with downwardly-extending spurs or spuds i, which, when the device is operated, hold it against backward movement.

The operation is as follows: The device is 70 placed in position, with the pivoted bracket on the end of the sliding rack-plate bearing against the board to be held in place. The bell-crank lever is then raised, which causes the jointed arm G to slide rearwardly upon 75 the sliding rack-plate B. The bell-crank lever is then lowered, which causes the jointed arm to straighten and move the sliding rack-plate B forwardly. As the said plate B is being moved forward, the pivoted pawl or stop 80 is raised by the teeth of the same, and as soon as the bell-crank lever has been lowered to its fullest extent the pivoted stop or pawl engages the sliding rack-plate and prevents the backward movement of the same, thus allowing the 85 strip or board to be secured in place.

It will be seen that by the employment of my improved floor-clamp the boards may be laid very closely together, from the fact that they are held securely in position while being 90 nailed or otherwise secured.

My improved floor-clamp is simple in its construction, effective in its operation, strong and durable, and may be readily and easily operated.

Having fully described my invention, what 95 I claim as new, and desire to secure by Letters Patent, is—

In a floor-clamp, the combination, with a base having upwardly-extending arms, of a 100 bell-crank lever pivoted between the latter, a jointed arm, G, pivoted at its rear end to the

base and pivotally connected at its joint with the bell-crank lever by a short arm, *j*, a sliding rack-plate adapted to be engaged by the forward end of the jointed arm, a bracket having a groove on its outer side, and a pawl pivoted between the arms *E*, and adapted to engage the rack-plate, as set forth.

In testimony that I claim the foregoing as my own I have hereto affixed my signature in presence of two witnesses.

CHARLES F. DEARTH.
